SHIPPING CONTAINER

Victor Willoughby, Ridgewood, N. J., assignor to
American Car and Foundry Company, New
York, N. Y., a corporation of New Jersey

Application July 22, 1931, Serial No. 552,376

5 Claims. (Cl. 220—1.5)

This invention relates to shipping containers particularly adapted for use with railway cars of the gondola or flat car type for the storage and transportation of merchandise.

5 One object of this invention is the provision of a container for storing and transporting less than car lots of merchandise, which container is exceptionally strong and durable in operation and is easy and inexpensive to manufacture.

10 Another object of this invention is the provision of a shipping container for handling fractional car lots of merchandise which is formed of an underframe comprising side and end sills and transverse and longitudinal stiffeners all riveted together to form a skeleton base for the container.

15 A further object of this invention is the provision of a shipping container of the kind described having corner posts provided with post stiffeners, certain of which are formed to define reinforced door posts.

20 This invention further contemplates the provision of a container which is adapted to be lifted and moved about by a crane or the like, which container includes side walls having tension members connected to a base frame to which the side walls are secured, the tension members being spaced on each of the side walls and having means for engagement by the lifting tackle, and compression members secured to the side walls adjacent their upper edges and connecting the upper ends of said tension members whereby when the container is lifted horizontal components of the lifting strains will be removed from the roof and side walls of the container.

25 A still further object of this invention is the provision of a shipping container adapted to be transported on a railway car or a motor truck, said container having means on its side walls for engagement by suitable tackle to permit the container to be lifted and moved about, the means being spaced on each side of the container and the container being stiffened adjacent the lifting means by a strut that serves to distribute the stresses to which the container is subjected.

30 Other objects and advantages of this invention will be apparent from the following description taken with the accompanying drawings in which:

Figure 1 is a side elevation of the container.

35 Fig. 2 is a front end elevation of the container.

Fig. 3 is a rear end elevation of the container.

Fig. 4 is a plan view of the interior of the container taken just above the floor line, the view being taken on the line 4—4, Fig. 1.

40 Fig. 5 is a sectional view taken on the line 5—5, Fig. 4.

Fig. 6 is a sectional view taken on the line 6—6, Fig. 1.

45 Fig. 7 is a sectional view taken on the line 7—7, Fig. 2.

Fig. 8 is a sectional view taken on the line 8—8, Fig. 9.

Fig. 9 is a fragmentary front elevation of a portion of the construction shown in Fig. 2, the view being taken above the upper door hinges. 5

Fig. 10 is a detail view showing the construction of the carlins and purlins.

Fig. 11 is a sectional view taken on the line 11—11, Fig. 10.

Fig. 12 is a sectional view at the lower left-hand portion of Fig. 2, below the lower door hinges, the view being taken on the line 12—12, Fig. 13.

Fig. 13 is a sectional view taken on the line 13—13, Fig. 12.

Fig. 14 is a sectional view taken on the line 14—14, Fig. 4.

Fig. 15 is a sectional view taken on the line 15—15, Fig. 14.

Fig. 16 is a fragmentary view showing the lower end of one of the stiffening ribs, and 20

Fig. 17 is a sectional view taken on the line 17—17, Fig. 16.

Referring now more particularly to the drawings in which similar characters of reference are used to indicate similar parts in the several views, 25 the shipping container of the present invention comprises in the main, a base, A, side walls B, a fixed or closed rear end wall C, a front end wall D and a roof E, the container being formed completely of metal, as will hereinafter more fully 30 appear. The base A is strong and formed of material suitable for carrying the load while the body of the container may be formed of a lighter material such as aluminum, if desired, all within the scope of the present invention. 35

The base A comprises side and end sills 2 and 4, respectively, channel shaped in the instance shown, and having upper and lower flanges 6 and 8, respectively, the ends of which are mitered and adjacently arranged (see Fig. 13) and 40 are connected together by suitable means such as the gussets 10 riveted as at 12 to the upper surfaces of the lower flanges 8 of said sills, thus forming a substantially rectangular frame in which the adjacent sills are inwardly facing to provide 45 a symmetrical exterior.

As clearly shown in Figs. 4 and 5, a plurality of underframe stiffeners 16 and 18 are provided, said stiffeners being Z-shaped in section and stiffeners 16 extending between and being supported by the lower flanges of the side sills 2. 50 The rivets 19 or other suitable fasteners are provided for connecting the stiffeners 16 to the side sills. The Z stiffeners 18 extend longitudinally of the underframe and between adjacently 55 arranged transverse stiffeners 16 and also between the end sills 4 and the adjacent transverse stiffeners 16. The longitudinal stiffeners 18 are supported at their ends by the lower flanges of the end sills and stiffeners 16 and by 60

angle clips 20 riveted to the webs 22 of the stiffeners 16 (see Fig. 14) and the ends of the stiffeners 18 are preferably coped as at 24 to permit the projection of the ends of the stiffeners beneath the upper flanges of the end sills and stiffeners 16 whereby the upper flanges 26 will be in substantially the same horizontal plane as the upper flanges of the end sills and stiffeners 16 thereby providing an underframe in which all elements thereof may support a plate metal floor 28 riveted to the upper flanges of the side and end sills and the upper flanges of the stiffeners 16 and 18, as shown clearly at 29. From the description just above it is apparent that the end portions of the container adjacent the bottom thereof, and more particularly the end sills, are reinforced against buckling due to end shocks to which the container may be subjected by the provision of the longitudinally arranged stiffening elements connected to the end sills and the adjacent cross stiffeners 16. It will also be apparent that the metal floor 28 at the end portions of the container is supported by a plurality of supporting elements. The construction just described is in contradistinction to a container in which the end sills and lower end portions of the container are not stiffened against end shocks thus rendering the construction easily susceptible to deformation because the end sill alone receives full impact. The plate metal floor 28 may be of one piece or of a plurality of pieces, as indicated in Fig. 15, wherein adjacent edges of the sheets forming the plate metal floor 28 are overlapped as at 31 and riveted to the upper flanges 35 of the stiffeners.

From the above description it is believed that those skilled in the art will see that an underframe has been provided which is of skeleton formation, but which, because of its construction, is exceptionally strong to withstand service conditions.

The side walls B and rear end wall C are formed of pairs of metal plates 30 and 32, respectively, overlapped along a horizontal line and riveted together as shown at 34; plates 32 having their lower edges lapping the channel sills and riveted thereto as at 36. The adjacent side edges of the side and end walls lap the legs of angle shaped corner posts 38 and are riveted thereto and to internal post stiffeners 40, as shown at 42, the post stiffeners being substantially co-extensive with the posts 38, but having their lower ends welded to the plate metal floor and to the sills, as shown at 44, see Figs. 4 and 13, while the lower ends of the posts 38 lap adjacent side and end sills and are riveted thereto, as shown at 46.

At the front end wall D the post stiffeners 40 have one leg inwardly flanged as at 48 in the general direction of the longer axis of the container to define a door post and then rearwardly bent as at 50 to define a door post stiffener. To provide additional strength at the front end wall corner stiffeners 52 are provided adjacent each post stiffener 40, said corner stiffeners comprising clips or gussets, each having a base 54 riveted to the plate metal floor 28 and the adjacent side and end sills, and an attaching flange 56 complementary to the post stiffener 40 and riveted to the latter, as shown at 58. In effect, the corner posts each comprise a pair of vertical members between which the side and end walls are positioned and to which said walls are connected, one of said members being substantially angle-shaped, while the other member

(member 40) comprises the legs 60 united by a diagonal brace 62, which latter forms a strut between the legs of the post, thereby stiffening the entire post assembly. The front end wall D comprises in the main, a door header 64 and doors 66, the latter being hingedly connected as at 68 to the corner posts and each including a rectangular frame formed of connected stiles and rails 70, Z-shaped in the instance shown, and a front plate 72, all such as shown in Figs. 7 and 8. The doors are preferably stiffened by horizontally arranged Z-bars 74 while the upper vertical chord 76 of the upper door rail 70 overlaps the vertical leg 78 of an angle shaped upper door frame member 80 which extends between opposite corner posts and is riveted as at 82 to the door header 64, the lower edge of the latter being outwardly and downwardly flanged as at 84 to define a water-shed. The member 80 is connected at its ends to the corner posts by angle brackets 85 the vertical legs of which are riveted to the corner posts (see Fig. 9) and the horizontal legs 87 rest upon and are riveted to the horizontal leg of the said member 80. As clearly shown in Fig. 2, the header 64 extends between and is riveted to the corner posts at this end of the container. The header is further stiffened by vertical braces 86 as is clearly shown in Fig. 2.

The roof E may be formed of a single metal sheet or plate if desired but in the instance shown is formed of a plurality of adjacently arranged sheets 88 the adjacent edges of which are overlapped on a line transverse to the longitudinal dimension of the container and are connected together in any suitable manner as by welding or riveting. The roof sheets include downwardly extending flanges 89 which overlap the upper edges of the side and end walls and are riveted thereto as shown at 90. The upper portions of the side and end walls are inwardly flanged as at 95 to stiffen the walls and to provide supporting elements for the roof. It will be obvious that the present construction avoids the necessity of using independent members such as angles, channels, etc. to form side and end plates because the flanges 89 and the portions of the walls overlapped by the roof constitute, in effect, such plates. The roof E is stiffened by carlins 92, one arranged at the joint formed by the overlap of adjacent roof sheets (see Fig. 1) and the others having their ends riveted to the inwardly extending horizontal flanges 94 of angle shaped struts S, the vertical legs 96 of which are connected to the upper edges of the side walls by rivets as clearly shown in Fig. 6. The carlins 92 reinforce or stiffen the roof transversely of the container but in addition to these members the roof is further stiffened by purlins 98 formed in sections and connected to the carlins 92 by means of gussets 100, (see Figs. 10 and 11).

In service, containers such as herein shown and described are subjected to severe strains and stresses due to the lifting and moving about by cranes or the like, and the present day demand is for a container which will be relatively light in weight but strong enough to withstand service conditions. The elimination of the usual side and end plates reduces the weight of the container and means must be provided for removing the horizontal components of the lifting strains from the side walls, end walls and roof and the struts S are provided for this purpose. These struts S do not extend from end to end of the container but, as shown more clearly in Fig. 1, the ends of

the struts terminate adjacent lifting ears 102 secured to the container by the before mentioned rivets 90 and each comprising overlapped strap portions 104 defining an eye 106 in which is positioned a lifting loop 108; the loops 108 being adapted for receiving suitable hoisting tackle whereby the container may be lifted and moved about by a crane. Secured between the portions 104 of the lifting ears are the upper ends of downwardly diverging ribs 110 the lower ends of which are riveted to the side sills (see Fig. 1) and serve to stiffen the side walls as will be apparent. The side walls B are further stiffened by vertical ribs 112 extending between the roof and the side sills and arranged between the sets of ribs 110. It has been found desirable to further stiffen the side walls, particularly the portions 32 thereof by means of horizontal ribs 114 which extend between the ribs 110 as shown in Fig. 1. The ribs 110, 112 and 114 are all connected to the side walls in any suitable manner as by being riveted at 116. To those skilled in the art it will be obvious that the ribs 110 are tension members which are connected to the base frame and are arranged in sets; the upper ends of the tension members being connected to the lifting ears 102. As will be apparent in Fig. 1 the struts extend between and connect the upper ends of the tension members 110 and therefore serve as compression members. It will also be apparent that when the container is lifted and moved about the horizontal components of the lifting strains are removed from the roof E and the side walls B and are transmitted directly to the sturdy base frame.

The rear end wall C is reinforced by vertical ribs 118 extending between the roof and the end sill and riveted thereto and to the plates 30 and 32 forming the end wall as shown at 120.

For retaining the doors in normal closed position suitable locking means 122 are provided which may be conventional.

From the description herein it is believed that the construction of the container of the present invention will be fully apparent to those skilled in the art. Those skilled in the art will recognize that a container such as shown and described herein may be fabricated of lighter material than those in present day use. The side walls, end walls and roof may be made of aluminum if desired and due to the fact that the horizontal components of the lifting strains are removed from the walls and roof by the present construction the most effective strength members comprise a skeleton frame. The container is particularly adapted for handling fractional car loads of merchandise and hence is adapted for use with railway cars such as gondola cars or flat cars but obviously the construction shown and described may be utilized satisfactorily in some containers of smaller size for handling, storing and transporting smaller amounts of merchandise.

The drawings herein illustrate one embodiment of the invention but it is to be understood that they are for illustrative purposes only and various changes in the form and proportions of the construction may be made within the scope of the appended claims without departing from the spirit of the invention.

I claim:

1. A container comprising connected side walls and end walls, a roof supported by said walls and having marginal flanges overlapping the upper

edges of the said walls and constituting side and end plates, a base to which the side and end walls are connected, spaced sets of tension members secured to the side walls and base, compression members secured to the inner surfaces of the side walls adjacent their upper edges and extending only between the sets of tension members and connected to the latter, and lifting elements to which the tension members and compression members are connected.

2. A container comprising connected side walls and end walls, a roof supported by said walls and having marginal flanges overlapping the upper edges of the said walls and constituting side and end plates, a base to which the side and end walls are connected, spaced sets of tension members secured to the side walls and base, compression members secured to the inner surfaces of the side walls adjacent their upper edges, said compression members extending only between and being connected to these sets of tension members and having inturned flanges constituting roof supporting elements, and lifting elements to which the tension and compression members are connected.

3. A container for fractional car lots comprising connected side walls and end walls having their upper edge portions inwardly flanged to constitute roof supporting elements, a roof resting upon said flanges and having depending marginal flanges overlapping the side and end walls and constituting side and end plates, a base to which the side and end walls are connected, spaced sets of tension members secured to the side walls and base, compression members secured to the inner surfaces of the side walls adjacent the inturned flanges thereof and provided with inwardly extending flanges underlying the before mentioned side wall flanges, said compression members extending only between and being connected to the sets of tension members, lifting elements to which the tension members and compression members are connected, and transversely arranged roof bracing elements connected to the inwardly extending flanges of the compression members.

4. In a container, a base frame including connected side and end sills, side and end walls lapping the sills, angle-shaped corner posts connecting adjacent side and end walls, a floor supported by the base frame, internal post stiffeners connected to the posts including intermediate angular portions spaced from the posts and forming struts, the post stiffener at the front end of the container having one edge thereof extending beyond the corner post and being inturned inwardly to form a door post, and corner stiffeners secured to the floor and flanged upwardly against said post stiffeners, portions of said internal door post overlapping said stiffeners, and a roof secured to the upper portion of the side and end wall.

5. In a container, a base frame including side and end sills, side and end walls lapping the sills, angle-shaped corner posts connecting adjacent side and end walls, a floor supported by the base frame, an internal post stiffener at the front end of the container having an intermediate portion spaced from the corner post to define a strut, one edge of said stiffener extending beyond the post and being inturned to define a door post, and a roof secured to the upper portion of the side and end walls.

VICTOR WILLOUGHBY.
